UNITED STATES PATENT OFFICE.

PASQUALE LUIGI CIMINI, OF BUFFALO, NEW YORK.

REVOLVING PLATFORM FOR APARTMENT FURNITURE.

1,278,108.

Specification of Letters Patent. Patented Sept. 10, 1918.

Application filed December 12, 1916. Serial No. 136,452.

To all whom it may concern:

Be it known that I, PASQUALE L. CIMINI, a citizen of the United States, and a resident of Buffalo, in the county of Erie and State of New York, have invented a new and Improved Revolving Platform for Apartment Furniture, of which the following is a full, clear, and exact description.

My invention relates to furniture for 10 apartments, forming part of the rooms thereof and so arranged that a room may be easily transformed into a living room, sleeping room or a kitchenette, etc., as the occasion may require.

15 An object of the invention is to provide a simple and inexpensive arrangement whereby with the least number of rooms the largest comfort can be obtained.

Reference is to be had to the accompanying drawings, forming part of this specification, in which like characters indicate corresponding parts in all the views.

Figure 1 is a plan of an apartment provided with an embodiment of my invention; 25 Fig. 2 is a vertical section on line 2—2, Fig. 3, of the standpipe or column on which the revoluble platform carrying the various furniture is supported;

Fig. 3 is a horizontal section on line 3—3, 30 Fig. 4;

Fig. 4 is an elevation of the kitchenette section of the furniture as seen on lines 4—4, Fig. 3;

Fig. 5 is a vertical section on line 5—5 35 showing the bed in operative position and the mechanism associated therewith;

Fig. 6 is a horizontal section on line 6—6, Fig. 5 showing the bed mechanism in plan;

Fig. 7 is a section on line 7—7, Fig. 4; and 40 Figs. 8, 9 and 10 show different apartments each provided with an embodiment of my invention whereby one or more rooms associated with the arrangement may be transformed into any of the desired rooms, 45 as previously mentioned.

Referring to the drawings, 11 is a platform, supported on suitable rollers 12, to which motion may be imparted by a suitable motion-transmission mechanism 13. This 50 mechanism may be actuated either by a crank or a motor. In rotating the rollers, the platform is caused to rotate therewith. A tubular column 14 rises from the central part of the platform. Said column houses 55 the standpipe 15, which pipe has a revoluble section 16 preferably mounted on suit-

able ball bearings 17. The movable section carries T's 18 at the ends thereof, the lower T being connected by a conduit 19 to the drain of a tub 20, for which the standpipe 15 constitutes the wastepipe. The upper T 18 receives an extension 21 of a revoluble supply conduit 22 housed in the standpipe 15. The extension 21 is provided with suitable valves 23 for supplying water to the tub 20.

The tub 20 rests on partition walls 24 which rise from the platform along the column 14 and subdivide the space about the column into four compartments A, B, C 70 and D. The partitions in the central part of the platform are at right angles to each other and disposed radially on the platform through their major part. A closet 25, is mounted above the tub 20 on the partitions 24. Closets 26 are secured to the lateral extensions of the said partitions on each side of the tub 20. Above one of the said closets 26 an ironing-board 27 is hinged to the partition and is normally maintained against the partition by a suitable locking member 28. Above the other partition 26 a suitable stove 29 is provided to complete the kitchenette. Within the tub, preferably, a washbasin 30 is provided, the said basin being mounted 85 on trunnions 31 within the tub so that the same can be swung from the operative to the inoperative position, the said basin being so shown in dotted lines in Fig. 5.

A bed frame 32 is provided in the compartment C opposite the kitchenette compartment. The said frame carries an axle 33 which bears in the lateral extension of the partitions 24 which form the said compartment C. A gear 34 is provided on the axle to rotate therewith. It meshes with a pinion 35 bearing in a frame 36 which is free to turn on the axle 33. The pinion has a shaft section 37 through the medium of which the gear 34 may be operated and the 90 bed frame 32 swung in or out of the compartment.

The free end of the bed frame is provided with a leg frame 38, a swinging portion 39 of which extends above the bed frame to 105 form an abutment for the bedding to be placed on the bed frame. The shape of said portion 39 is such that the same can easily fit into the angular portion of the compartment C formed by the partitions 24. A 110 swinging head section 40 is connected to the bed frame 32 at a suitable distance from the

portion 39. This head portion has a similar shape to that of portion 39. Both of said portions are geared by a mechanism 41 to the gear 34 to swing inwardly and jam the bedding on the frame when said bed frame 32 is moved into the inoperative position, as indicated in dotted lines in Fig. 5, thereby preventing the disarrangement of the bedding on the frame.

10 A suitable closet 42, in the shape of a sideboard, is mounted in the compartment B. The said sideboard has casters 43 engaging tracks 44 provided in the platform 11 and running toward the edge of the platform, so 15 that the sideboard may be moved out of the compartment B to partially overhang the platform 11. A closet 45 is mounted in compartment D. It has preferably the shape of a dresser, provided with casters 20 running on tracks 44 for permitting the shifting of the closet 45 in and out of compartment D.

Generally the platform 11 is so mounted that at least two compartments thereof face 25 openings 46 in the walls of the apartment which it is to serve (see Fig. 1). In one of the walls the transmission mechanism 13 is mounted to impart movement to the platform, so as to bring any of the desired compartments 30 in front of the desired opening.

The room which is to serve as a sleeping room has in the wall thereof adjacent the opening a shaft 47 to which motion may be imparted by a crank 48. A shaft section 49 35 is connected to the shaft 47 by a universal joint 50. This shaft section 49 can be connected to the shaft section 37 by a coupling 51. The motion is imparted to said shaft section 37 from the crank, thereby permitting the lowering of the bed frame into the 40 room, and vice versa.

As shown in Fig. 1, the bathroom has an opening with which any of the compartments may be brought into register. For 45 example, the compartment D may be brought into register with said opening thereby making the dresser closet accessible from the bathroom. When the kitchenette is to be utilized for washing purposes, compartment A will be brought into register 50 with the bathtub; and when it is to be used as a kitchenette, it will be brought into register with the opening 46 of the room which serves as a sleeping room. Normally 55 the sideboard will occupy opening 46 of the

room, but it is self-evident that any of the closets may be normally maintained in front of any of the openings.

In Figs. 8, 9 and 10 the arrangement is shown to be accessible from more than two 60 sides. For example, in Fig. 8 it is accessible from all four sides, thereby transforming the rooms in accordance with the position of the compartment. In Figs. 9 and 10 the compartments are accessible from three 65 sides, thereby leaving only one of the compartments normally inaccessible; but the said compartments can be brought into register with either of the openings in a manner as previously described. 70

I claim:

1. Apartment structure comprising in combination a revoluble platform, a standpipe projecting from the platform, a tubular column on said platform housing the 75 standpipe, partitions subdividing the platform into a plurality of compartments, a tub associated with one of said compartments, said standpipe having a revoluble section, a drainpipe from the tub to the 80 revoluble section, a revoluble water-supply pipe in said standpipe, and a valve-controlled extension from the supply pipe to the tub.

2. Apartment structure comprising in 85 combination a standpipe, a platform revoluble about the standpipe, a tubular column on the platform housing the standpipe, partitions associated with the platform and column for dividing the platform about the 90 column into a plurality of compartments, said standpipe having a revoluble section within the column, a revoluble water-supply pipe in the standpipe having a valve-controlled outlet through the revoluble section 95 and column into one of the compartments, and a drain pipe from the same compartment to the revoluble section of the standpipe.

3. An apartment structure comprising in 100 combination, a revoluble platform, a frame mounted on the platform to swing in a vertical plane, motion-transmission means on the platform associated with the frame, and operating means outside of the platform having means for engaging the motion-transmission means when said motion-transmission means are brought into alignment with said operating means. 105

PASQUALE LUIGI CIMINI.
